UNITED STATES PATENT OFFICE.

JAMES M. WALSH, OF MILWAUKEE, WISCONSIN.

BRIDLE.

Original application filed May 22, 1924, Serial No. 715,121. Divided and this application filed February 7, 1925. Serial No. 7,590.

To all whom it may concern:

Be it known that I, JAMES M. WALSH, a citizen of the United States, and resident of Milwaukee, in the county of Milwaukee and State of Wisconsin, have invented new and useful Improvements in Bridles, of which the following is a description, reference being had to the accompanying drawings, which are a part of this specification.

10 This invention relates to improvements in bridles, and more particularly to means for adjusting the bit, and is a divisional application of an application for improvements in bridles; Serial No. 715121; filed May 22, 15 1924.

It is one of the objects of the present invention to provide a bridle having a novel connecting means which will permit adjustments between the bit and head-stall and 20 eliminates the use of apertured straps which tend to weaken a bridle.

A further object of the invention is to provide a bridle in which the bit rings are adjustably carried by means of chains instead of straps as commonly used.

25 A further object of the invention is to provide a bridle in which a movement of the bit will not cause the bit ring or connecting means to become detached from the head-stall, the connecting means employed being link chains so that movements of the bit will not be transmitted to the upper links of the chains which engage the connectors of the head-stall.

30 A further object of the invention is to provide a bridle which is of very simple construction, is strong and durable, is inexpensive to manufacture, and is well adapted for the purpose described.

35 With the above and other objects in view, the invention consists of the improved bridle and its parts and combinations as set forth in the claims and all equivalents thereof.

In the accompanying drawing in which 40 the same reference characters indicate the same parts in all of the views:

Fig. 1 is a fragmentary view of the head-stall and bit of a bridle constructed in accordance with the invention; and

45 Fig. 2 is a sectional view taken on line 2-2 of Fig. 1.

Referring now more particularly to the drawing it will be seen that the numeral 5 indicates the improved bridle which consists 50 essentially of the head-stall straps 6 and 7

carried by a connector 8, a bit ring 9, and a connecting link chain 10 carried by the bit ring and adjustably secured to the connector.

The connector is formed of a metallic frame substantially square in form with an integral angularly bent portion 11 separated from the main connector portion by a transverse rib 12. A hook 13 is formed integrally with the mid-portion of the transverse rib 12, said hook being curved as clearly shown in Fig. 2 with the end 14 thereof extending through the connector opening and slightly beyond the plane of the frame 8.

The connector is adapted to have attached thereto the head-stall straps 6 and 7 and one of the upper links of the chain 10 is engaged by the hook 13 of the connector. The lowermost link of the chain carries a bit ring 9 to which is secured one end of a bit 15.

Obviously, the connector 8 permits adjustments of the chain 10 to lower or raise the bit 15. Adjustments of the chain are attained by engaging the hook 13 with any of the links of the chain to lengthen or shorten the same. To engage a link with the hook, it is merely necessary to pass the link through the opening of the connector frame and drop the link over the end 14 of the hook, as shown in dotted lines in Fig. 2. The chain will then assume the position on the hook shown in full lines in Figs. 1 and 2 and will be securely retained in place. A movement of the horse or bit will not dislodge the chain because the links can move with respect to each other and movement of the bit or lower links will not move the upper link engaged by the hook. Hence, it will be impossible for the chain to become accidentally detached from the connector.

To prevent the hook 13 from projecting, so as to rub or become uncomfortable to an animal wearing the bridle, a leather flap 16 is provided. Said flap is sewed to the head-stall straps 6 and 7 and normally is positioned as shown in full lines in Fig. 2. However, when it is desired to adjust the bit, the flap 16 may be bent outwardly as shown in dotted lines in Fig. 2 to expose the hook 13.

From the foregoing description it will be seen that the improved bridle is of very simple and novel construction, and is well adapted for the purpose set forth.

What I claim as my invention is:

1. The combination with a bridle includ-

ing a head-stall and bit, a chain connected to the bit, and a connector carried by the head-stall and formed with a hook portion extending into the plane of the connector, said hook portion being selectively engageable with any of said chain links.

2. The combination with a bridle including a head-stall and bit, a chain connected to the bit, and a connector connected to the head-stall, said connector being formed with side portions, end portions, a cross portion, and a curved hook portion extending outwardly from the medial portion of said cross portion and then curving inwardly through the plane of said side portions, said hook portion being selectively engageable with any of said chain links.

3. The combination with a bridle including a head-stall and bit, a chain connected to the bit, a connector carried by the head-stall and formed with a curved hook portion extending into the plane of the connector, said hook portion being selectively engageable with any of said chain links, and a flap secured to the head-stall and covering the projecting portions of said hook portion.

4. The combination with a bridle including a bit, a chain carrying a bit ring secured to one end of the bit, a metallic connector, said connector being formed with side por-

tions, end portions, a cross portion, and a curved hook portion extending outwardly from the medial part of said cross portion and then curving inwardly through the plane of said side portions, said hook portion being selectively engageable with any of said chain links to adjust the position of the bit, strap members secured about the sides and ends of said connector, and a leather flap secured to said strap members and covering the projecting portions of said hook portion, said flap being bendable to afford access to said hook portion.

5. The combination with a bridle including a head-stall and bit, a connector secured to the head-stall and formed with a hook portion extending into the plane of the connector, and connecting means connected to the bit and detachably engaged by the hook portion of said connector, said connecting means being formed of a plurality of sections movable with respect to each other so that movement of a lower section of said connecting means will not move an upper section to accidentally disengage it from said hook, any portion of the connecting means being selectively engaged by said hook.

In testimony whereof, I affix my signature.
JAMES M. WALSH.
